UNITED STATES PATENT OFFICE.

KARL FRITJOF NYSTRÖM, OF ST. LAMBERT, QUEBEC, CANADA.

CAR-TRUCK.

1,288,146.

Specification of Letters Patent. Patented Dec. 17, 1918.

Application filed December 29, 1917. Serial No. 209,456.

To all whom it may concern:

Be it known that I, KARL FRITJOF NYSTRÖM, a subject of the King of Sweden, and resident of 80 Edison avenue, in the town of St. Lambert, in the Province of Quebec, in the Dominion of Canada, have invented certain new and useful Improvements in Car-Trucks, of which the following is the specification.

The invention relates to improvements in car trucks as described in the present specification and illustrated in the accompanying drawings that form part of the same.

The invention consists essentially of the novel features in the side frames, whereby the upper and lower arch bars are distanced at the central portions in such a manner as to secure an equitable distribution of the load.

The objects of the invention are to devise a truck, that will be serviceable and strong and withstand rough usage, rapid changes of temperature and sundry other causes, which tend toward the loosening of bolts and other fastenings, to furnish a better carrier for greater loads and generally to provide an efficient, cheap and durable structure for the aforesaid purposes.

In the drawings, Figure 1 is an elevation of the side frame.

Fig. 2 is a longitudinal sectional view of the side frame on the line A—B in Fig. 1.

Fig. 3 is a vertical sectional view on the line C—D in Fig. 1.

Fig. 4 is a plan view of the side frame from above.

Like numerals of reference indicate corresponding parts in each figure.

Referring to the drawings, the numeral 1 indicates the upper arch bar and the numeral 2 the lower arch bar.

As customary the upper arch bar is a compression member and the lower arch bar a tension member, these members being brought together at the ends and fastened by bolts or rivets.

From the joinings the upper arch bar 1 slightly rises and the lower arch bar 2 sharply descends to the central column 3, said column 3 being preferably U-shaped in cross section and having four sides 4, 5, 6 and 7 forming a frame for the bolster and its supporting springs.

The vertical sides 4 and 7 project in-

wardly at 8 to form a fastening for the bolster, said projections terminating intermediate of the depth of the column to permit the removal of the bolster.

The reinforcing ribs 9 and 10 extend from the upper portions of the sides 4 and 7 and the former project into and are integral with the brake beam brackets 11.

Immediately under the side 5 the sides 4 and 7 are slotted at 12 to receive the upper arch bar 1, which extends through said column and is rigidly secured thereto by the rivets 13.

The side flanges 14 project from the lower side 6 of the column 3 and support the spring plank 15.

The lower arch bar 2 extends through the lower channel of the column 3 and the tie strap 16 extends under the said lower arch bar and the two members are secured to the column 3 by the rivets 17.

It will be seen that by this construction, the vertical sides 4 and 7 of the column 3 become tension members, as the weight of the car body transmitted through the bolster draws on the lower arch bars and said vertical sides and through this tension strain bear on the upper arch bars, which in their turn relieve the tension strain on the lower arch bars and column thereby equitably distributing the load.

Various changes may be made in the construction without departing from the spirit of the invention so long as they are within the scope of the claim for novelty following.

What I claim is:

In a side frame for car trucks, an upper arch bar, a lower arch bar, and a frame having top, bottom, and sides and forming a flanged opening for a bolster, the vertical tension members of said frame being integral with the transverse members at top and bottom and having openings immediately below the top transverse member through which said upper arch bar is inserted, said bottom transverse member being channeled in the under side to receive said lower arch bar.

Signed at the city of Montreal, Quebec, Canada, this 27th day of November, 1917.

KARL FRITJOF NYSTRÖM.
